JEPHTHA G. HOLLINGSWORTH, OF KANSAS CITY, MISSOURI.

DENTAL-MATERIAL-CONDENSING APPARATUS.

1,168,635.

Specification of Letters Patent. Patented Jan. 18, 1916.

Application filed January 7, 1915. Serial No. 1,024.

To all whom it may concern:

Be it known that I, JEPHTHA G. HOLLINGSWORTH, a citizen of the United States, residing at Kansas City, in the county of Jackson 5 and State of Missouri, have invented certain new and useful Improvements in Dental-Material-Condensing Apparatus, of which the following is a specification.

This invention relates to dental material 10 condensing apparatus and more particularly to apparatus for condensing material in molds to form fillings to be transferred to and cemented in tooth cavities corresponding to such molds, a method and apparatus 15 for the preparation of such fillings being illustrated and described in patents numbered and dated respectively 1,099,248, June 9, 1914, and 1,101,439, June 23, 1914.

Prior to the invention forming the subject 20 matter of this application the filling material has been condensed by hand tamping or pressure and I have found that such method is very fatiguing to the operator particularly in making cold gold fillings where a 25 forcible tamping pressure is required to reduce the gold to a homogeneous mass.

My object therefore is to produce apparatus for condensing cold gold fillings and the like with greater facility, ease, and efficiency than by the method heretofore employed.

With this general object in view, the invention consists of certain novel and peculiar features of construction and organization 35 as hereinafter described and claimed; and in order that it may be fully understood reference is to be had to the accompanying drawing, in which—

Figure 1, is a central vertical section of 40 apparatus for tamping or condensing loose gold into a homogeneous or integral mass by foot power. Fig. 2, is a vertical section taken on the dotted line I—I of Fig. 1. Fig. 3, is a section of a block for use when it is 45 desired to condense or tamp a filling into a mold having an undercut portion. Fig. 4, is a fragmentary vertical section showing an adjustable means for suspending the tamping or compressing tool or implement.

50 In the said drawing where like reference characters identify corresponding parts in all the figures, 1 is a hollow base provided with an opening 2, in its top and a standard 3, which terminates in an arm 4, overhanging the opening 2. In Fig. 1, the arm 4 is

provided with a socket 5, at its underside, and secured to the lower side of said arm is a spring plate 6, bifurcated at 7, at its free end.

8 indicates one form of pressing or tamping tool for attachment to the lower end of a handle portion 9, equipped with a headed shank 10, at its upper end, and to support the tool or implement, the narrow part of the shank is slipped into the bifurcation of 65 the spring plate 6, and the headed end into the socket 5. By this construction it will be seen that under a slight pull on the handle, the spring plate will yield to permit the tool to be removed.

To assist in holding the tool in vertical 70 position, its handle is embraced by a spring yoke 11, secured to the end of a rod 12, adjustably clamped to standard 3, by a clamping screw 13.

A lift plate 14, fits snugly in opening 2, of the base 1, and is provided with depending guide flanges 15. Connecting said plate to a cross-piece 15^a, of the base, which rests upon a table T, or the like, is a retractile spring 80 16, for effecting a rapid lowering of the plate after each upward movement imparted to the same, in a manner hereinafter explained.

A transverse rock shaft 17, is journaled in 85 the side walls of the base 1, and is provided within the latter with a pair of upwardly and forwardly extending arms 18, connected by a cross-piece 19. A rock-frame consisting of a pair of parallel upwardly and rearwardly extending arms 20, overlying the cross-piece 19, and fitting between the arms 18, and mounted upon a rock-shaft 21, at their front ends. The rock-shaft is journaled in the side walls of the base, and the 90 free or rear ends of the arms 20, are connected by a cross-piece 22.

A lever 23, for rocking shaft 17, is arranged within the base and extends rearwardly from the shaft 21. It is connected 100 at its rear end by a chain or equivalent connection 24 to a foot lever 25 hinged at 26 below the table and provided with a rubber foot piece 27. To avoid a chattering noise in the operation of the foot lever, a cushion 28 is interposed between the top of the base and the lever 23 and a cushion 29 is interposed between the lever and the table.

The device is operated by the attendant placing his foot upon plate 27 and alter- 110

nately applying and relaxing pressure thereon, the depression of the lever imparting a short upward movement to the lift plate and the removal of the pressure from the lever permitting the parts to be returned instantly through the retraction of spring 16, which is tensioned by the upward movement. It will thus be seen that vertical vibratory movement of the plate 14 can be produced and that the speed and force of such movement is entirely under the control of the operator.

The lift frame forms a support for a pedestal or block 30, provided with upwardly projecting lugs 31. A mold 32 containing a cavity not shown, corresponding to the cavity in the tooth to be filled, is placed upon the pedestal and the mold is provided with a groove 33 to receive the lug 31, whereby turning movement or accidental dislodgment of the mold is prevented. The pedestal is held lightly vertically below the tool and with each upward movement of the lift plate gold or other filling material placed in the cavity is tamped through impact against the lower end of the tool, it being obvious that the operator can shift the position of the pedestal slightly after each impact so that the entire surface of the filling material may be brought into contact with the tool, and it is also obvious that the operator by maintaining pressure upon the foot lever can maintain the lift plate in an elevated position and shift the pedestal upon the lifting plate so as to get in effect a heavy burnishing action on the filling material through the instrumentality of the tool. He can thus follow the irregular contour of the cavity and condense the marginal portion of the filling more effectively than by the tamping action.

With cavities which extend at an angle to the perpendicular there is presented an undercut surface as shown at S, Fig. 3, and to tamp material along this surface efficiently I have found it desirable to provide a false base to support the pedestal at such an angle that the undercut side of the cavity shall occupy a substantially vertical position. This base is numbered 34 and adapted to rest directly upon the lift plate 14 and to be shifted thereon by hand and carry the pedestal and mold with it. To retain the pedestal properly in position its upper side is provided with a recess or channel 35 within which the base rests and is capable of rotation, should it be desired to rotate the mold with respect to the tool as in burnishing operations, though it is obvious that a burnishing action can be obtained by moving the false base upon the lift plate.

Provision has been made for the vertical adjustment of the tamping device or tool, as in tamping some materials it is desirable to shorten the range of movement of the lift

65 plate. This construction is illustrated in

Fig. 4, where a screw 36 is mounted in arm 4 and is provided at its lower end with a socket 37 corresponding to socket 5 and like the latter adapted for the reception of the headed end of the shank 10, and to reliably support the tool a U-shaped spring 38 is secured to the screw and has its lower arm underlying the screw and bifurcated at 39 for the reception of the shank of the tool.

It will be apparent that with an apparatus of the character outlined, the hands of the operator are left free except as he must shift the mold with its supporting parts to bring the tamping tool in contact with the entire surface of the filling in the mold. Consequently the operation can be performed without the fatigue incident to performing the tamping operation by hand. Of course a motor or its equivalent may be employed for imparting vibratory action to the lift plate, but it is believed the operation of the same manually is more satisfactory, in that practice will soon enable the operator to apply the force most suitable for the particular work on hand. Furthermore a manually operated apparatus is essential in small towns or places where other power is unavailable.

From the above description it will be apparent that I have produced a dental material condensing apparatus embodying the features of advantage enumerated as desirable, and I wish it to be understood that while I have illustrated and described what now appears to be the preferred form of the invention, I reserve the right to make all changes falling within the spirit and scope of the appended claims.

I claim:

1. A dental material condensing apparatus, comprising a suitably supported tool, a plate for the support of a mold, and means for effecting relative rapid vibratory approaching movement between the tool and plate whereby filling material in the mold may be tamped therein by the said tool.

2. A dental material condensing apparatus, comprising a suitably supported tool, a plate for the support of a mold, means for effecting relative rapid approaching movement between the tool and plate whereby filling material in the mold may be tamped therein by said tool, and yielding means for quickly effecting reverse movement between said tool and plate.

3. A dental material condensing apparatus, comprising a suitably supported tool, means for supporting a mold in longitudinal alinement and in a tilted position with respect to the tool, and means for effecting relative rapid vibratory approaching movement between the tool and mold-holding means whereby filling material in the mold may be tamped therein by said tool.

4. A dental material condensing appa-

- ratus, comprising a suitably supported tool, a plate provided with a circular recess in its upper side for the support of a mold tool so that the latter shall be capable of 5 rotatable adjustment, and means for effecting relative rapid vibratory movement between the tool and plate whereby filling material in the mold may be tamped therein by the tool.
- 10 5. A dental material condensing apparatus, comprising a pendantsly supported tool, a base provided with an opening underlying said tool, a plate for up and down sliding movement in said opening and for 15 the support of a mold containing material to be tamped, foot-lever actuated means for effecting quick upward movement of the plate in said opening, and a spring for reversing such movement.
- 20 6. A dental material condensing apparatus, comprising a pendantsly supported tool, a base provided with an opening underlying said tool, a plate for up and down sliding movement in said opening, a pedestal resting on said plate, a mold secured on said pedestal vertically under the tool, crossed devices pivotally carried within the 25 base at their lower ends and engaging said plate at their upper ends, a cross piece secured to one of said devices and engaging the under side of the other of said devices, a spring holding the plate yieldingly depressed, and lever actuated means for im- 30
- parting upward movement to the pivoted device provided with the said cross piece. 35
7. In a dental material condensing apparatus, a base provided with an opening and a standard, the latter terminating at its upper end over the opening, a plate fitting in said opening for the support of a mold containing material to be condensed, a tool detachably suspended vertically from the standard over said opening and means for effecting relative rapid vibratory movements between the plate and tool whereby 40 the filling material may be tamped within 45 the mold.
8. In a dental material condensing apparatus, a base provided with an opening and a standard, the latter terminating at its upper end over the opening, a plate fitting in the opening for the support of a mold, containing material to be condensed, a tool detachably suspended vertically from the standard over said opening, means carried 50 by the standard and engaging the tool to assist in holding the latter against swinging movement, and means for imparting rapid vibratory movement to the plate toward and from the tool. 55
- 60

In testimony whereof I affix my signature in the presence of two witnesses.
